[57] CLAIM

The ornamental design for a communications antenna,
as shown and described.

DESCRIPTION

FIG. 1 is a top plan view of a communications antenna
showing my new design;

FIG. 2 is a rear elevational view thereof;

FIG. 3 is a right side elevational view thereof, the left
side being a mirror image;

FIG. 4 is a bottom plan view thereof; and,

FIG. 5 is a front elevational view thereof.

The broken line showing of the support feet is for illus-
trative purposes only and forms no part of the claimed
design.

Fig. 2.

Fig. 5.

Fig. 1.

Fig. 3.

Fig. 4.
